REFRIGERATION

Curtis C. Coons, North Canton, Ohio, assignor to
The Hoover Company, North Canton, Ohio

Application June 12, 1940, Serial No. 340,038

5 Claims. (Cl. 62—119.5)

This invention relates to the art of refrigeration and more particularly to a novel absorption refrigerating system having a solution circuit so constructed and arranged that the same produces improved results.

It has been shown by long experience that boilers for three-fluid absorption refrigerating systems of the domestic type should be constructed in the shape of an elongated tube having a central heat passageway therethrough. This construction has been found to be the most advantageous in the type of system under consideration without causing deleterious or dangerous conditions due to incomplete combustion or condensation of moisture from the gases flowing through the central boiler tube.

The boilers of the above mentioned type, however, are thermally inefficient due to the localized heating area therein and due further to the fact that the large draft tube which is made necessary for safety reasons does not provide the most advantageous heat transfer arrangement between the hot gases and the fluids in the system.

Another disadvantage of the boiler construction previously used results directly from the fact that the liquid tends to stagnate in certain sections of the boiler without taking a useful part in the vaporizing process.

Accordingly, it is an object of the present invention to provide an absorption refrigerating system embodying a solution circuit and vaporizing construction which will overcome the above-mentioned disadvantages of the prior art.

More specifically, it is a principal object of the present invention to provide a three-fluid absorption refrigerating machine including a boiler in which a local circulating circuit is set up so arranged that the same is subjected to the hottest gases which are available for heating the solution and which is also so constructed and arranged as to effectively prevent stratification of inactive bodies of liquid in portions of the boiler.

It is a further object of the invention to provide a boiler construction for a three-fluid absorption refrigerating system in which a strong local circulation is set up in which liquid is withdrawn from the boiler, conducted through an intensely hot zone and then is returned to another portion of the boiler which tends to improve the heat transfer and which also enables the boiler to operate at more uniform temperatures throughout the extent thereof, thus improving its operating efficiency.

Other objects and advantages of the invention will become apparent as the description proceeds

when taken in connection with the accompanying drawings, in which:

Figure 1 is a diagrammatic representation of a refrigerating apparatus embodying the present invention.

Figure 2 is an elevational view in partial section of a boiler-analyzer construction incorporated in the apparatus of Figure 1.

Figure 3 is a diagrammatic representation of a modified form of the invention, and

Figure 4 is an elevational view, partly in section, of a boiler construction utilized with the form of the invention illustrated in Figure 3.

Referring now to the drawings in detail and first to Figure 1 thereof, there is illustrated a three-fluid absorption refrigerating apparatus comprising a boiler B, an analyzer D, an air-cooled rectifier R, a tubular air-cooled condenser C, an evaporator E, a gas heat exchanger G, a tubular air-cooled absorber A, a solution reservoir S, and a circulating fan F which is driven by a suitable electrical motor M. These elements are suitably connected by various conduits, to be described hereinafter, to form a plurality of gas and liquid circuits constituting a complete refrigerating system.

The above described refrigerating system will be charged with a suitable refrigerant, such as ammonia, a solvent therefor, such as water, and a pressure equalizing medium which is inert with respect to the refrigerant and solvent, preferably a dense inert gas like nitrogen.

The boiler will preferably be heated by a fuel burner H which is supplied with fuel by a mechanism under the control of a regulating valve V.

The application of heat to the boiler B liberates refrigerant vapor from the strong solution normally therein contained. The vapor so liberated passes upwardly through the analyzer D in counterflow relationship and in contact with strong solution returning to the boiler. The vapors then pass from the upper portion of the analyzer D to the upper portion of the condenser C by way of the conduit 11 which includes the rectifier R.

The absorber, gas heat exchanger and evaporator together form a circuit for the inert gas which includes a circulating fan F. The gases discharged from the circulating fan F are conveyed therefrom to the bottom part of the evaporator E by way of the conduit 12, the gas heat exchanger G, and the evaporator gas supply conduit 13. After traversing the evaporator the inert gases are conveyed from the upper portion thereof to the bottom portion of the absorber A by way of

the conduit 15, the gas heat exchanger G, and the conduit 16. After flowing upwardly through the absorber A the inert gases are returned to the circulating fan F by means of the conduit 17, thus completing the inert gas circuit.

The refrigerant vapor which is supplied to the condenser C is liquefied therein and the liquid is conveyed from the bottom portion of the condenser to the bottom portion of the evaporator by way of the conduit 14 and a conduit 18 which includes a downwardly extending U-shaped portion and opens into the bottom portion of the evaporator gas supply conduit 13. The condenser sides of the conduits 14 and 18 are vented by means of a conduit 19 to the rich gas side of the gas heat exchanger to provide a vent for the condenser and to subject the condenser, rectifier, boiler and analyzer to a pressure lower than that prevailing in the evaporator gas supply conduit 13. Consequently there is a pressure balancing liquid column formed in the condenser side of the conduit 18 to a height sufficient to balance the pressure differential existing between the conduits 13 and 15.

Though the evaporator may be of any desired construction, it is preferred, in accordance with the present invention, to be of the type in which the inert gas circulates therethrough with a velocity sufficient to propel the liquid refrigerant through the evaporator as it is evaporating. A specific example of an evaporator of this type is disclosed and claimed in the co-pending application of Curtis C. Coons and William H. Kitto, Serial No. 386,395, filed April 2, 1941, which is a continuation-in-part of application Serial No. 220,189, filed July 20, 1938, now Patent No. 2,328,196, dated August 31, 1943. An anti-blocking drain 25 is connected between a solution conduit 26, to be described hereinafter, and the bottom of the evaporator E. The connection between the conduit 25 and evaporator E is such that the evaporator is not drained completely but liquid cannot accumulate therein above a predetermined level.

The lean solution formed in the boiler B by the expulsion of refrigerant vapor therefrom is conveyed from the boiler to the reservoir S by way of the conduit 28, the liquid heat exchanger L, and a finned looped pre-cooling conduit 21. The upper portion of the reservoir S is vented to the suction conduit 17 of the circulating fan F by means of a conduit 22, whereby the liquid level in the reservoir S will be raised to the maximum possible height due to the fact that the same is vented from the lowest pressure area in the system.

The solution supplied to the reservoir is conveyed therefrom to the suction conduit 17 adjacent its point of connection with the upper end of the absorber A by way of a gas lift pump conduit 23. Pumping gas is supplied to the conduit 23 beneath the liquid level normally prevailing therein by a conduit 24 which connects to the discharge conduit 12 of the circulating fan F. Thus, the absorption solution is elevated into the absorber by gas lift action.

The absorption solution flows downwardly through the absorber in counterflow relationship with the rich mixture of pressure equalizing medium and refrigerant vapor which is flowing upwardly therethrough from the evaporator. The solution absorbs refrigerant vapor from the mixture and the resulting heat of absorption is rejected to cooling air flowing over the exterior

walls of the absorber and the cooling fins attached thereto.

The strong solution formed in the absorber A drains to the bottom portion thereof from which point it is conveyed to the upper portion of the analyzer D by way of the conduit 26, the solution heat exchanger L, and the conduit 27, thus completing the absorption solution circuit externally of the boiler-analyzer system.

10 Fuel is supplied to the burner H through a supply conduit 30 which is under the control of the solenoid valve V. A by-pass conduit 29 is provided around the valve V to maintain a small pilot or igniting flame on the heater H during periods when the valve V is in closed position.

A suitable thermostatic control mechanism 31 is provided to be responsive to evaporator temperature and operates a switch which is interposed between the electrical conductors 32 and 33 to break the circuit therein. The conductor 32 is connected to a source of supply as is the conductor 34. The conductor 33 is connected to a conductor 35 which connects between the motor M and the solenoid valve V. The conductor 34 connects directly to a conductor 36 connected between the valve V and motor M. Consequently closure of the switch mechanism to complete the circuit between the conductors 32 and 33 simultaneously energizes the motor to operate the circulating fan and energizes the valve V to open position to maintain a full flame on the burner H. Opening of the circuit between the conductors 32 and 33 de-energizes the motor and valve to render the fan and heater inoperative.

35 Referring now to Figure 2, it will be seen that the boiler B comprises an elongated tubular body portion 38 which is pierced by central combustion tube or flue 39 which, as seen in Figure 1, is positioned to receive hot products of combustion from the burner H adjacent the right hand end thereof as shown in the drawings. The left hand end of the combustion tube 39 connects to a suitable products of combustion disposal flue 40.

40 The analyzer D comprises an upright tubular body 42 which opens at its lower end into the upper side of the boiler body 38 adjacent the right hand end thereof as is shown in Figure 2. A plurality of staggered baffle plates 43 are provided within the analyzer D to provide a tortuous path of flow for the ascending vapors and the descending solution which is supplied by the conduit 27.

45 In accordance with the present invention a mechanism is provided for setting up a strong local circulation within the boiler body 38. This mechanism comprises a conduit 45 which opens into the bottom central portion of the boiler body 38. The conduit 45 extends to the right hand end of the boiler, as indicated in Figure 2, where it has a vertically extended section 46 which extends into the bottom portion of the combustion flue 39. The section 46 is joined to an upwardly inclined elongated section 47 which extends to the left hand end, as viewed in Figure 2, of the combustion tube 39 slightly beyond the confines of the boiler body 38. The U-bend section 48 of the tube extends through the wall of the extended portion of the combustion tube 39 and opens into the top end portion of the boiler body 38.

50 The conduit circulator 45 to 48 which includes the section 47 directly in the combustion tube 39 provides a means for setting up a strong local circulation within the boiler. Also the tube 47

represents a very hot heating zone and one which exceeds the temperature of any other portion of the boiler. This is due to the fact that the hot gases discharged from the burner H into the tube 39 are quickly cooled at their outer sides and tend to maintain an inner core of extremely hot gases. The tube 47, however, is directly subjected to this inner core of hot gases and contains a vastly greater ratio of heat conducting metal to fluid body than is the case between the conducting tube 39 and the boiler 38, wherefore extremely hot conditions prevail within the tube 47.

This arrangement causes a local circulation due to the vapor bubbles evolved in the tube 47 which operates as a vapor lift pump to pull solution from the bottom portion of the boiler to conduct the same through a hot zone and to return the heated solution to the top portion of the boiler.

The arrangement of the boiler assembly eliminates stagnation. Stagnation at the left hand end of the boiler B is fairly well prevented by reason of the connection thereto of the lean solution offtake conduit 20. Likewise stagnant conditions at the extreme right hand end of the boiler are fairly well prevented due to the disturbance therein of the vapors flowing into the bottom portion of the analyzer column and also because of the liquid flowing from the analyzer into the boiler. Another factor tending to eliminate undue stagnation at the right hand end of the boiler results from the fact that this is the portion of the boiler which directly and immediately receives the hot flame from the burner H.

The central portion of the boiler, however, connects at its bottom into the tube 48, thus preventing stagnation at that point. Due to the very hot conditions prevailing in the tube 47 considerable solution is vaporized therein as well as refrigerant which is previously dissolved in the solution. It is therefore desirable that this liquid and vapor be returned to the boiler at a point remote from its connection with the analyzer in order to prevent the solution vapor from entering the analyzer and at a point close to the offtake conduit 20 in order to permit the very lean solution discharged from the conduit 47 to find its way to the absorber without traversing all of the boiler. Both these objects are well met by having the conduit 48 open into the boiler at the end thereof remote from the analyzer and directly over its connection with the conduit 20.

The solution vapor which is discharged from the conduit 48 as well as the vapors of the refrigerant travel to the right along through the liquid contained in the boiler body 38. In this process the solution vapors, having a much higher boiling point than the refrigerant vapors, are condensed in the boiler and serve further to heat the contents thereof and further serve to agitate the fluids therein contained which in turn improves the transfer and evolution of refrigerant vapor.

The culminating effect of all these factors is to produce a boiler construction having a remarkably high efficiency and reliability.

Referring now to Figure 3, a different construction of apparatus is disclosed. In this form of the invention the heat applied to the boiler B' by means of the burner H' generates refrigerant vapor therein which operates through a vapor lift pump construction to lift the lean solution through the vapor lift conduit 50 into the separation and liquid return vessel 51. The vapor is then conveyed from the vessel 51 to the upper portion of the condenser C' by way of the con-

duit 52, a bubble type analyzer D' and the conduit 53 which includes the air-cooled rectifier R'.

The refrigerant liquid formed in the condenser drains from the bottom portion thereof through a conduit 54 into a U-shaped conduit 55 which opens into the upper end of the evaporator E'. The lean solution formed in the boiler flows through the vessel 51 back to the boiler and through the boiler in a manner to be described hereinafter. The lean solution ultimately is conveyed from the boiler to the upper portion of the absorber A' by way of the conduit 56, the liquid heat exchanger L', and the conduit 57.

The absorber in this form of the invention is shown as being of the plate type and will be provided with a suitable indirect air cooling system, not shown. The rich solution formed in the absorber is then returned therefrom to the analyzer D' by way of the conduit 58, the liquid heat exchanger L' and the conduit 59. The rich solution is then returned from the analyzer to the boiler by means of the conduit 60, thus completing the absorption solution circuit externally of the boiler B'.

The evaporator E' and the absorber A' and the gas heat exchanger G' are suitably connected to form an inert gas circuit. Lean gas formed in the absorber A' is conveyed from the upper portion thereof to the bottom portion of the evaporator E' by way of the conduit 62, the gas heat exchanger G' and the evaporator gas supply conduit 63. The inert gas flows upwardly through the evaporator in counterflow relationship to the liquid refrigerant which is evaporating into the inert gas. The resulting enriched gas is conveyed from the upper portion of the evaporator E' to the bottom portion of the absorber A' by way of the conduit 65, the gas heat exchanger G' and the conduit 66.

The evaporator is drained of non-condensable material by means of a conduit 67 which opens into the rich gas side of the gas heat exchanger, thus discharging the non-condensable material into the bottom portion of the absorber A' where it mixes with strong solution.

A suitable pressure vessel which compensates the system for variations in temperature of the atmosphere is provided. The pressure vessel P is connected to the bottom portion of the absorber by means of a conduit 68 and to the condenser side of the U-shaped conduit 55 by means of a conduit 70.

This form of the invention utilizes the well known gravity type of gas circulation in which the inert gas is circulated by the density differential between the cold rich gas descending from the evaporator and the warm lean gas ascending from the absorber. In order to facilitate gas circulation the system will preferably be charged with a light inert gas such as hydrogen. The absorbent and refrigerant will be water and ammonia, respectively, as in the form of the invention described in connection with Figures 1 and 2.

The supply of fuel to the burner H' is controlled by a suitable control mechanism 71 which will be arranged in a known manner to respond to the temperature of the evaporator E'.

Referring now to Figure 4, the construction of the boiler and its associated parts is illustrated and will be described in detail.

The boiler B' comprises a tubular elongated body portion 73 which is pierced by a combustion tube 74 adapted to receive hot products of combustion from the burner H'. The annular space formed between the elements 73 and 74 is divided

by means of an annular partition 75 into right and left hand boiler spaces 76 and 77, respectively. The vapor lift pump 50 opens into the left hand end of the space 77, as viewed in Figure 4, and the separation and return conduit 51 opens into the right hand end of the chamber 76.

A local solution circuit within the boiler section 76 is set up by means of the conduit 80 which extends from the bottom central portion of the boiler section 76 to the left, as viewed in Figure 4, then makes a return bend and extends through the entire length of the combustion tube 74 rising as it progresses to the right and finally opens into the extreme right hand end and upper portion of the chamber 76.

Likewise the chamber 77 is provided with a local solution circulating mechanism which comprises a conduit 81. The conduit 81 opens into the bottom central portion of the chamber 77, extends to the right, as viewed in Figure 4, executes a return bend and then extends the entire length of the combustion tube 74, rising as it progresses to the left, as viewed in Figure 4. The tube 81 then has a return bend portion which opens into the upper extreme left hand end portion of the chamber 77.

As shown, the lean solution offtake conduit 56 opens into the bottom of the right hand end of the chamber 76 and the strong solution return conduit 80 opens into the bottom of the right hand end of the boiler chamber 77.

The operation of this form of the boiler construction is as follows: Strong solution entering through the conduit 60 is heated within the chamber 77 and vapor formed therein serves to elevate the solution through the vapor lift conduit 50 into the upper end of the vessel 51. A strong local circulation of solution through the boiler 77 is set up because of the tube 81 which is so arranged as to prevent stagnation of the solution in any part of the chamber 77. Also the high heat to which the conduit 81 is subjected in the combustion tube 74 serves to generate further refrigerant vapor from the solution and this weak solution and refrigerant vapor then discharge into the chamber 77 adjacent the vapor lift pump so that the vapor may immediately traverse the pump and may also be available for elevating the lean solution directly therethrough into the vessel 51. The pump 50 discharges into the vessel 51 and the vapor is taken off from the upper end thereof by means of the conduit 52. The solution supplied to the conduit 51 flows downwardly therethrough into the chamber 76 and ultimately from the chamber 76 through the conduit 56 to the absorber. A strong local circulation is set up within the chamber 76 by reason of the conduit 80 which is also so arranged with respect to the vessel as to prevent stratification or stagnation of any part of the liquid therein contained.

The arrangement of the conduit 80 is such that vapor formed therein is discharged into the chamber 76 adjacent its point of connection with the vessel 51 so that these vapors may immediately rise through the vessel 51 and join the vapors supplied to the upper portion thereof through the vapor lift pump 50. Furthermore, the lean solution which is discharged from the conduit 80 may immediately drop around the combustion tube 74 and be taken off through the conduit 56. This last procedure is greatly facilitated by the fact that lean solution is denser than rich solution and tends naturally to fall to the bottom portion of the enclosure 78.

Thus, in this form of the invention a plurality of circulating conduits are provided in order to prevent stagnation and to increase the efficiency of each section of the boiler.

It is within the purview of each form of the invention to provide the circulating tubes which extend through the boiler combustion tube with fins in order to increase the heat absorption area thereof, if desired. It is also within the purview of the invention to provide the form of the invention illustrated in Figure 1 with a plurality of circulating elements and to provide the form of the invention illustrated in Figure 4 with only one such element if desired, though it is believed that the arrangements shown constitutes the most efficient forms of domestic type refrigerating machine.

In each form of the invention a means is provided which effectively prevents stratification and stagnation of the solution in portions of the apparatus and which also simultaneously induces a circulation of liquid within the boiler itself and also in so doing removes liquid from the boiler, conducts it through an intensely hot zone where it is brought into contact with hot gases which normally are not efficaciously utilized to heat the boiler and then returns the resulting very lean solution and vapors to the boiler at a point or points at which the solution and vapor can be utilized most efficaciously. The terms "generator" and "boiler" are used interchangeably herein to designate a vessel or conduit subject to heating for the purpose of evolving vapor from a contained liquid.

Not only does the present arrangement improve the efficiency of vapor expulsion but it improves the entire refrigerating process by insuring that all the liquid therein contained continuously takes a part in the process and it also provides the absorber with leaner solution whereby the absorber is able to perform its function more efficiently.

While I have illustrated and described my invention in considerable detail, it is to be understood that the invention is not to be limited thereto but that changes and variations may be made without departing from the spirit thereof or the scope of the appended claims.

I claim:

1. In an absorption refrigerating system involving an evaporator and an absorber connected for circulation of an inert gas therebetween, a generator, means for liquefying refrigerant vapor produced in said generator and for supplying the liquid refrigerant to said evaporator, means connecting said absorber and generator for circulating an absorption solution therebetween, said generator comprising an elongated tubular body having a heating flue extending lengthwise therethrough, a combustible fuel burner positioned to discharge products of combustion through said flue, an analyzer extending above and opening into the top portion of said generator body adjacent the end thereof which receives products of combustion from said heater, said means connecting said generator and said absorber being arranged to supply strong solution to said analyzer and to withdraw lean solution from the bottom end portion of said generator body remote from said analyzer, and a circulation conduit including a portion extending lengthwise of and in said flue connecting the bottom central portion of said generator body to the top end portion thereof remote from said analyzer.

2. Absorption refrigerating apparatus comprising an evaporator, an absorber, means connecting said evaporator and said absorber for flow of inert gas therebetween, refrigerant vapor liquefying means arranged to discharge refrigerant liquid to said evaporator, a generator including a pair of heating chambers, means for conveying refrigerant vapor liberated in said generator to said liquefying means, means for conveying rich solution from said absorber to a first one of said heating chambers, vapor lift means for conveying solution from said first heating chamber to an elevation from which said solution may flow by gravity to said absorber, means for conveying solution elevated by said vapor lift means to a second one of said heating chambers, means for conveying solution from said second heating chamber, and means for circulating solution from at least one of said heating chambers through a high temperature heating chamber and back to the heating chamber from which it was taken.

3. Absorption refrigerating apparatus comprising an evaporator, an absorber, means connecting said evaporator and said absorber for flow of inert gas therebetween, refrigerant vapor liquefying means arranged to discharge refrigerant liquid to said evaporator, a generator including an elongated body, a flue for products of combustion piercing said body to form an annular heating chamber, means dividing said chamber into first and second heating sections, a combustible fuel burner for discharging products of combustion into said flue, vapor lift means operably associated with said first heating section for circulating absorption solution therefrom through said second heating section and into said absorber, means for conveying absorption solution from said absorber to said first heating section, means for conveying refrigerant vapors produced in said generator to said liquefying means, and means for circulating solution from each of said heating sections in heat exchange relationship with products of combustion flowing through said flue and back to the section of origin.

4. Absorption refrigerating apparatus comprising an evaporator, an absorber, means connecting said evaporator and said absorber for flow of inert gas therebetween, refrigerant vapor liquefying means arranged to discharge refrigerant liquid to said evaporator, a generator including an elongated body, a flue for products of combustion piercing said body to form an annular heating chamber, means dividing said chamber into first and second heating sections, a combustible fuel burner for discharging products of combustion into said flue, vapor lift means opening into the upper portion of said first section adjacent one end thereof, means opening into the upper portion of one end of said second section for supplying thereto solution discharged by said vapor lift means, means for conveying rich solution from said absorber to the bottom end portion of said first section remote from said vapor lift means, means for conveying lean solution to said absorber from the bottom of the end portion of said second section to which solution is supplied, conduit means having a portion extending lengthwise through said flue for conveying solution from the bottom portion of said first section to a portion thereof adjacent said vapor lift means, and conduit means including a portion extending lengthwise through said flue for conveying solution from the bottom portion of said second section to a portion thereof adjacent the point at which solution is supplied to said second section.

5. Vapor generating apparatus for use with an absorption refrigeration apparatus comprising an elongated generator body, a heating flue piercing said body lengthwise thereof, means separating said body into first and second heating chambers, means for supplying strong solution to said first chamber, means for conveying solution from said first chamber to said second chamber, means for removing weak solution from said second chamber, means for removing vapor produced in said chambers, and a conduit connected between spaced parts of one of said heating chambers and extending through said flue.

CURTIS C. COONS.
